DESIGN FOR A NAPKIN OR SIMILAR ARTICLE

Kenneth C. Hamilton, Milwaukee, Wis., assignor to Milwaukee Lace Paper Company, Milwaukee, Wis., a corporation of Wisconsin

Application March 27, 1946, Serial No. 127,985

Term of patent 14 years

(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for Napkin, or similar article, of which the following is a specification, reference being had to the accompanying drawing, forming part thereof, and in which:

The figure of the drawing is a face view of a quarter section of a napkin, or similar article embodying my new design. The remaining three quarters are identical with that herein disclosed and arranged in proper relation to complete the napkin.

I claim:

The ornamental design for a napkin or similar article, substantially as shown and described.

KENNETH C. HAMILTON.
